UNITED STATES PATENT OFFICE.

WILLIS D. A. PEASLEE, OF CORVALLIS, OREGON.

GAS-TURBINE.

1,255,924.

Specification of Letters Patent.

Patented Feb. 12, 1918.

Application filed January 17, 1917. Serial No. 142,969.

To all whom it may concern:

Be it known that I, WILLIS DHU AINE PEASLEE, a citizen of the United States, and a resident of Corvallis, in the county of Benton, State of Oregon, have invented a certain new and useful Improvement in Temperature-Reducing Means for the Blades of Gas-Turbines, of which the following is a specification.

10 My invention relates to turbine motors. The remarkably high efficiency of these motors is well known, but, nevertheless, the gas turbine has heretofore failed because of the destructive action on the blades of high temperatures of the gas jet.

Various means have been utilized in attempting to solve this difficulty in one of two methods, namely, either to cool the gas jet before its impact on the turbine blades, 20 or to cool the latter after the gas jet has been played upon them. In the first method—which consists in introducing steam into the gas and so cooling the latter to a temperature which will not corrode or 25 melt the blades—the efficiency of the jet is very largely sacrificed. The second method—which consists in playing a jet of steam on the blades after the gas jet has passed over them—was not efficient in preventing 30 the melting of the blades. Making the blades of a hollow water-cooled construction was also not successful on account of the poor circulation of the water due to the necessary small water passageway. This 35 resumé of the present state of the art, as understood by applicant, is given so that the purpose of this invention may be more clearly understood.

The object of my invention is to maintain 40 the temperature of the blades of the gas turbine below a destructive point.

I attain the object of my invention by maintaining a coating of cooling medium upon the backs of the blades of the motor 45 at all times while the gas jet is in contact with the opposite working faces of the blade; in this way permitting the gas jets to be applied at their maximum efficiency, but rendering the blades capable of resisting the high temperatures; in other words, the coating of the cooling medium keeping the temperatures of the blades below the destructive point.

In practice my invention may be carried

out as illustrated in the accompanying drawings, in which:

Figure 1 is a view of the rotor, the upper half being in elevation and the lower half in diametric section;

Fig. 1^a is a central section of the rotor 60 perpendicular to its axis of rotation;

Fig. 2 is a section of the combustion chamber and vanes of the rotor, taken through the center of the nozzle plane parallel to the axis of rotation of the rotor; 65

Fig. 3 shows a possible modification of my device to adapt it to multi-stage operation, and is a section through the vanes of the rotor and the fixed directive vanes;

Fig. 4 is a section through the center of 70 the fixed directive vanes shown in Fig. 3, and perpendicular to the plane of the latter; and

Fig. 5 is a diagrammatic plan of the complete device.

Referring first to Fig. 5, 13 is the rotor casing within which the motor is mounted on shafts 5, 6, supported in bearings 14, 15. 8 is a combustion chamber in which the oil or other gas-producing fuel is burned. Oil 80 is admitted to this combustion chamber through valve 9 from oil pump 24, and air is admitted to the combustion chamber 8 through valve 10 from air pump 25. 12, 26, 27 represent a means for igniting the fuel 85 when starting the device. The shaft 6 is made hollow and water supplied to it through stuffing gland and valve 28 from pump 26. Valves 9, 10 and 28 are controlled by means of linkage 23, by governor 21 90 driven by a belt 22 from the shaft 6. 16 is a passage by which the products of operation of the gas turbine are led to an auxiliary turbine 17, thence through passage 19 to condenser 20. Instead of being used 95 for driving an auxiliary turbine, the mixture of steam and exhaust gases may of course, be used in any other heat converting or transferring device.

Any means for utilizing the power, such 100 as an electric generator 18, may be attached to the driven shafts of the gas and steam turbines.

Referring to Figs. 1 and 1^a, the rotor of my device consists of two halves 1, 1, separated by means of spacers 2 and held firmly together by means of bolts 3, thereby forming a cavity within the rotor. The periph-

ery of the rotor is provided with vanes 4 for transforming the velocity energy of the gas jet issuing from the combustion chamber 8 through nozzle 11 into rotation energy of the rotor. These vanes 4 are so arranged that a passage 7 through the periphery of the rotor is provided, whereby water or other cooling medium, introduced by means of the hollow shaft 6 of the rotor into the cavity of the latter, is directed against the backs of said vanes 4, forming and maintaining a film of water over the entire back surface of these vanes.

Referring to Fig. 2, fuel, for example hydro-carbon oil, is introduced through an aperture controlled by the valve 9 by means of a pump 24, and air for combustion of this fuel is admitted through an aperture controlled by the valve 10 from pump 25. The combustion fills the chamber 8 with gas at high pressure and temperature. Nozzle 11, as common in devices of this kind, is designed to change the pressure energy of the gas into velocity energy, and the jet of gas issues from the nozzle 11 at very high velocity and temperature, impinging on vanes 4, which are driven at high velocity, thereby rotating the rotor of my device. This gas jet is at a very high temperature tending to reduce the strength of common structural materials, and it is therefore necessary to keep the vanes 4 below melting point by some cooling means, for example, provided by the passage 7, which furnishes and maintains a volume of water in contact with the back of the vanes 4. This water, being turned into steam, extracts the heat from the vanes so rapidly that their temperature is maintained at a safe working value. The mixture of steam from this cooling water and the exhaust gases then fills the casing 13 of the gas turbine, and this mixture might be discharged into the atmosphere and wasted, but I conceived the idea of utilizing it in an auxiliary turbine 17, which may or may not be connected to the same shaft as the gas turbine rotor, though shown connected to the gas turbine shaft in Fig. 5. In this way the energy extracted from the gas turbine in cooling the vanes is usefully employed, so the total output of my device is the sum of the available energies of the gas and auxiliary turbine.

In order to maintain the temperature of the vanes 4 at approximately a constant point, the amount of water, or other cooling medium, introduced by means of the pump 26, through hollow shaft 6, is varied by means of the governor 21 and its connections, simultaneously with the variation of the fuel required, so that an increase in fuel carries with it a corresponding increase in the cooling medium.

As shown in Figs. 1, 1^a and 2, this device is a single stage machine, and since the vanes

4 extract a large portion of the velocity from the gas jet, the speed in revolutions per minute will be rather high. It is entirely possible and feasible to reduce this speed by making the device a multi-stage unit, extracting the velocity from the gas jet in increments. The means for accomplishing this is shown in Fig. 3, wherein the gas jet, after leaving vanes 4 with approximately half its original velocity, and in a direction opposite to the movement of the vanes 4, is turned in direction by the vanes 29, which are fixed in the casing 13 by means of the shroud rings 32. After being turned by these fixed vanes 29, it is directed on vanes 4', which are mounted on the rotor of the turbine in a row parallel to the vanes 4. A large portion of the velocity is extracted by said vanes 4', which are cooled by means of the passages 7' exactly as are the vanes 4 above described. The fixed vanes 29 are cooled by means of water, or other cooling medium, projected against their backs by means substantially as shown in Fig. 4, wherein the cooling medium is carried in pipe 31, and from thence by pipes 30 through the casing 13, so directed as to perform and maintain a film of water against the backs of the vanes 29.

While my device is shown as an impulse turbine, of course I do not confine myself to such specific use.

I claim:

1. In a gas turbine motor, the method of maintaining the blades at a safe working temperature consisting in projecting and maintaining a coating of cooling medium upon the backs of the blades.

2. In a gas turbine motor, means for constantly applying a covering of cooling medium to the backs of the blades of the motor, and an outlet for the waste products.

3. In a gas turbine motor, means for constantly applying a covering of cooling medium to the backs of the blades of the motor, an outlet for the waste products, and means for regulating the amount of cooling medium supplied proportionately to the amount of fuel consumed by the motor.

4. In a gas turbine motor, means for constantly applying a covering of cooling medium to the backs of the blades of the motor, an outlet for the waste products, a valve controlling the fuel supply, a valve controlling the supply of cooling medium, and means for controlling said valves.

5. In a gas turbine motor, means for constantly applying a covering of cooling medium to the backs of the blades of the motor, an outlet for the waste products, a valve controlling the fuel supply, a valve controlling the supply of cooling medium, and automatic means for controlling said valves relatively to the change of load.

6. In a gas turbine motor, means for con-

stantly applying a covering of cooling liquid to the backs of the blades of the motor, an outlet for the waste products, an auxiliary turbine, and means for directing the vapor

5 generated from said liquid in its application to said gas turbine blades against the blades of said auxiliary turbine.

7. In a gas turbine motor, means for constantly applying a covering of cooling liquid 10 to the backs of the blades of the motor, an outlet for the waste products, an auxiliary turbine, means for directing the vapor generated from said liquid in its application to said gas turbine blades against the blades of 15 said auxiliary turbine, and means for applying the energy of the gas and steam turbines combined as a driving power.

8. In a gas turbine motor, means for constantly applying a covering of cooling liquid 20 to the backs of the blades of the motor, an outlet for the waste products, an auxiliary turbine, means for directing the vapor generated from said liquid in its application to said gas turbine blades against the blades of 25 said auxiliary turbine, a valve controlling the fuel supply, a valve controlling the supply of cooling liquid, and means for controlling said valves.

9. In a gas turbine motor, means for constantly applying a covering of cooling liquid 30 to the backs of the blades of the motor, an outlet for the waste products, an auxiliary turbine, means for directing the vapor generated from said liquid in its application to said gas turbine blades against the blades of 35 said auxiliary turbine, a valve controlling the fuel supply, a valve controlling the supply of cooling liquid, and automatic means for controlling said valves relatively to the 40 change of load.

10. In a gas turbine motor, a rotor provided with an internal cavity, said rotor having peripheral blades, means for introducing a cooling medium into said cavity, 45 peripheral apertures connected with said cavity and adapted to direct a stream of cooling medium against the backs of said blades, and a discharge for waste products.

11. In a gas turbine motor, a rotor provided with an internal cavity, said rotor having peripheral blades, means for introducing a cooling medium into said cavity, 50 peripheral apertures connected with said cavity and adapted to direct a stream of cooling medium against the backs of said blades at an angle, and a discharge for waste products.

12. In a gas turbine motor, a rotor provided with an internal cavity, said rotor 55 having peripheral blades, means for introducing a cooling medium into said cavity, peripheral apertures connected with said cavity and adapted to direct a stream of cooling medium against the backs of said 60 blades, a discharge for waste products, and

means for regulating the amount of cooling medium supplied proportionately to the amount of fuel consumed.

13. In a gas turbine motor, a rotor provided with an internal cavity, said rotor 70 having peripheral blades, means for introducing a cooling medium into said cavity, peripheral apertures connected with said cavity and adapted to direct a stream of cooling medium against the backs of said 75 blades, a discharge for waste products, a valve controlling the fuel supplied, a valve controlling the supply of cooling medium, and means for controlling said valves.

14. In a gas turbine motor, a rotor provided with an internal cavity, said rotor 80 having peripheral blades, means for introducing a cooling medium into said cavity, peripheral apertures connected with said cavity and adapted to direct a stream of 85 cooling medium against the backs of said blades, a discharge for waste products, a valve controlling the fuel supply, a valve controlling the supply of cooling medium, and automatic means adapted to control 90 said valves relatively to the change of load.

15. In a gas turbine motor, a rotor provided with an internal cavity and having parallel rows of peripheral blades spaced apart, an intermediate row of stationary 95 blades on the interior periphery of the turbine case, means for introducing a cooling medium into said cavity of the rotor, peripheral apertures connected with the cavity of the rotor and adapted to direct a stream of 100 cooling medium against the backs of the blades of the rotor, a passageway for a cooling medium in the circumference of the case, and apertures connected with this passageway adapted to direct a stream of cooling 105 medium against the backs of said intermediate blades.

16. In a gas turbine motor, a rotor provided with an internal cavity and having parallel rows of peripheral blades spaced 110 apart, an intermediate row of stationary blades on the interior periphery of the turbine case, means for introducing a cooling medium into said cavity of the rotor, peripheral apertures connected with the cavity of 115 the rotor and adapted to direct a stream of cooling medium against the backs of the blades of the rotor, a passageway for a cooling medium in the circumference of the case, apertures connected with this passageway 120 adapted to direct a stream of cooling medium against the backs of said intermediate blades, and means for regulating the amount of cooling medium supplied proportionately to the amount of fuel consumed.

17. In a gas turbine motor, a rotor provided with an internal cavity and having parallel rows of peripheral blades spaced apart, an intermediate row of stationary 130 blades on the interior periphery of the tur-

bine case, means for introducing a cooling medium into said cavity of the rotor, peripheral apertures connected with the cavity of the rotor and adapted to direct a stream of cooling medium against the backs of the blades of the rotor, a passageway for a cooling medium in the circumference of the case, apertures connected with this passageway adapted to direct a stream of cooling medium against the backs of said intermediate blades, a valve controlling the fuel supplied, a valve controlling the supply of cooling medium, and means for controlling said valves.

18. In a gas turbine motor, a rotor provided with an internal cavity and having parallel rows of peripheral blades spaced apart, an intermediate row of stationary

blades on the interior periphery of the turbine case, means for introducing a cooling medium into said cavity of the rotor, peripheral apertures connected with the cavity of the rotor and adapted to direct a stream of cooling medium against the backs of the blades of the rotor, a passageway for a cooling medium in the circumference of the case, apertures connected with this passageway adapted to direct a stream of cooling medium against the backs of said intermediate blades, a valve controlling the fuel supply, a valve controlling the supply of cooling medium, and automatic means adapted to control said valves relatively to the change of load.

WILLIS D. A. PEASLEE.
